HYDRAULIC JACK

Joseph J. Mueller, St. Joseph, Mich., assignor to
 Auto Specialties Manufacturing Company, St.
 Joseph, Mich., a corporation of Michigan

Application March 12, 1945, Serial No. 582,281

4 Claims. (Cl. 254—10)

1

This invention relates to what are known as "floor jacks."

Among the objects of the present invention is to provide a jack of the present construction which is composed of a minimum number of parts, many less parts than commercial jacks of this general type which are now on the market.

Another object of the invention resides in providing a simplified means for actuating the high pressure pump cylinder from the handle mechanism in a plurality of adjustable arcuate segments all of which lie in a common plane.

Another object of the invention is to provide an improved floor jack having elongated handle means for actuating the high pressure pump cylinder and also for actuating the pressure release valve which permits the liquid to return from the ram cylinder back to the reservoir, wherein simple means is provided for detachably removing said handle from the mechanism which it actuates, and particularly wherein when the handle is so removed the relief valve will be inaccessible for operation so that the jack cannot be inadvertently lowered.

Yet another object of the invention resides in providing a construction wherein the ram cylinder and ram, the high pressure pump cylinder and piston, and the pressure relief valve and its actuating mechanism are all in a common plane centrally of the ram cylinder, thereby enabling the use of but one universal joint connection between the pressure relief valve mechanism and the reciprocating handle which conjointly operates the high pressure pump piston and the high pressure relief valve, in one case by a reciprocating movement and in the other case by a turning movement.

Another object of the present invention is to provide a spring pressed ball release valve in the ram cylinder chamber which is operable when the pressure gets too high in the ram cylinder chamber, to open the valve and permit the liquid under pressure to return back to the reservoir.

Another object of the present invention is to provide a floor jack having a ram cylinder and ram disposed in substantially horizontal position with respect to the floor when the jack is in operative position and wherein the high pressure pump cylinder and piston and the pressure relief valve and its operating mechanism are disposed at an angle of substantially thirty degrees with respect to the horizontal, thereby providing a much more simplified construction of floor jack, whereby a number of parts of the floor jack may be eliminated, including an extra universal mech-

2

anism between the relief valve and the handle operating mechanism, and whereby also the parts are accessible from a standing position of the operator.

Yet another object of the present invention is to provide a floor jack having mechanism providing a relatively slower power lifting pump and a relatively faster or speed pump constructed and arranged so that when lifting the liquid-carrying member of the jack up to the load, both the power pump and the speed pump are operative, speedily to move the load member up to the load engaging position and thereafter the power pump only operates and the speed pump automatically cuts out.

Yet another object of the invention resides in providing a combined power or pressure operating pump with a speed or accelerating pump, which are operable quickly to get the load-carrying member up to the load and thereafter the mechanism is operable to lift the load by the power pump alone, the speed pump automatically cutting out, and this mechanism is operable irrespective of whether it is on a floor jack or any type of hydraulic jack suitable for its adaptation.

Yet another object of the invention is to provide an hydraulic jack having both a speed pump and a pressure pump combined as one single pumping mechanism, together with automatic mechanism for cutting out one of the pumps after the load has been engaged.

These and other objects of the invention will be apparent from a perusal of the following specification when taken in connection with the accompanying drawings, wherein:

Figure 1 is a perspective view of the improved floor jack as it appears from the operating end;

Figure 2 shows perspective views of the associated parts of the jack;

Figure 3 is a partial plan sectional view taken on the line 3—3 of Figure 4;

Figure 4 is a longitudinal section taken on the line 4—4 of Figure 3;

Figure 5 is a sectional view of the left portion of the jack with the load-lifting member in raised position;

Figure 6 is a right hand end view of the jack with the handle portion broken away and a portion being shown in cross section;

Figure 7 is a sectional view showing an enlarged cross sectional view of the right hand portion of the jack, showing the operating mechanism and taken on line 7—7 of Figure 3;

Figure 8 is a perspective view showing associated parts of the lifting mechanism,

Figure 9 is a plan section taken on the line 9—9 of Figure 7;

Figure 10 is a longitudinal enlarged sectional view of a modified type of high pressure pump, taken on the line 10—10 of Figure 11;

Figure 11 is a view taken on the line 11—11 of Figure 13;

Figure 12 is an enlarged diagrammatic view showing the outline of the valve containing member in dot and dash lines, the valves and inter-connecting passageways being shown in full lines, to more clearly show their association with each other; and

Figure 13 is a plan section taken on the line 13—13 of Figure 10.

Referring now to the drawings in detail, the jack comprises a chassis shown particularly in Figure 2, which includes an enlarged body section formed of the two vertically disposed side plates 2 and 4 which at the forward end are joined by a top plate 6 having a forward and downward inclination. This top plate 6 has two rearwardly extending ears 8 and 10 spaced apart and provided with registering perforations 12 and 14 for the reception of a pivotal pin 16 hereinafter described. That section of the body portion to the rear of the top portion 6 is open at the top. At this point the two side plates 2 and 4 are united by a rear transversely disposed wall 14 which in turn has a parallel extension in the form of vertical walls 16 and 18 and which are rigidly and internally connected as at 20 by a top bridge portion for rigidity. These vertical side walls 16 and 18 are interconnected as at 22 by a transverse integral web which has a depressed cup-like cross groove 24 formed at the top thereof and the rearmost portion 26 of the body portion 22 is provided with registering openings for the reception of a stationary axle 30. A threaded pin 32 holds the axle 30 in position on the chassis 26. The opposite ends of the axle 30 carry stationary shields 36 and 38 which are pinned thereto as at 39 and 40 and casters or wheels 42 and 44 are rotatably mounted on the opposite ends of the axle 30.

On the underside, the body of the chassis is provided with two downwardly depending webs 46 and 48 for purposes of rigidity, and these webs are provided with registering apertures which extend parallel to and on the longitudinal axis of the chassis. At the larger end of the chassis the underside thereof is provided with downwardly depending partitions 50 and 52 which provide a mounting for the ram cylinder as shown in Figure 4. In other words, the underside of the chassis is substantially hollow except for certain of the rigidifying webs 46, 48, 50 and 52. The larger end of the chassis is provided with two integral outstanding shoulders 54 and 56 each of which is provided with a vertical bore rotatably to receive the turnable posts 58 and 60 of a caster wheel assembly comprising the ball bearing mounting 62, the front shield 64 on which are mounted the axle 66 and the rotatable caster 68. Means such as a pin 70 serves to hold the rotatable shank 58 of the casters in position on the shoulders 54 and 56, permitting them to rotate but preventing their withdrawal.

The larger end of the chassis body below the top 6 is formed as a vertical flat front plate 72 carrying the relatively large opening or bore 74 in line with the high pressure pump cylinder hereinafter referred to. In addition this plate 72 is provided with the four spaced apart threaded 75

bolt holes 76, which are adapted to receive the bolts 80 which bolt on that part of the hydraulic unit 82 in which the high pressure pump cylinder, the pressure relief valve, and the various ball controlled liquid passages are formed. As shown in Figure 2, this high pressure pump cylinder head or unit carries affixed to its the ram cylinder 84 and its projecting ram 86. As shown clearly in Figure 7, the ram cylinder 84 snugly fits and lies within the webs 50 and 52 which depend downwardly from the top portion 6 of the chassis. The head or unit 82 includes the integral vertical plate member 75 from which the ram cylinder 84 projects. When the bolts 80 are tightened 15 the vertical plate 75 of the head 82 is snugly tightened against the flat face 72 of the chassis, the ram cylinder 84 projecting into the opening 74 of this end of the chassis.

A load-lifting carriage, hereinafter described, 20 is mounted upon the pivotal pin 16 which passes through the perforated ears 8 and 10 of the chassis body 6 and also through a cross bore 96 of a downwardly extending section 98 of the load-lifting member. This member has two side 25 flanges 130 and 102 which carry spaced apart bearing bores 104 and 106 adapted to receive a pin 108 which carries a roller 110. The elongated load-lifting and lowering carriage 88 is shown in Figures 1 and 2. It is provided with 30 two vertical sides 90 and 92 and the transverse top 94. The forward end of this load-carrying member 94 is provided with two outstanding ears 112 and 114 which are perforated as at 116 and 118 to receive a pin 120 which supports a load lifting head 122. This head has a centrally disposed annular flange 124 receivable in a centrally apertured disc 126 the apertures of which receive the flange 124 of the load lifter 122 whereby the load lifter 122 may rotate as desired. The flange 126 40 is provided with two spaced apart ears 128 and 130 which are supported by the cross pin 120. In addition, the flange 126 carries two lateral toes 132 and 134 which receive a pin 136 connecting to links 138, 139, the other ends of which are pivoted as at 140 to the side plates 2 and 4 of the chassis 45 body. The purpose of these latter links is to maintain the rotatable work holder 122 in constantly horizontal position. When the load is in lowered position it will rest within the grooved cross slot 24 of the chassis, thereby enabling it to nest in compact relationship.

A plunger 142 is supported by the member 98 as shown in Figures 3 and 4, and seats against a shoulder 144 which is pivotally mounted on the pin 108. The plunger 142 is surrounded by a coil spring 146 and this spring has its opposite end retained in a cup-shaped member 148 which seats in the cross web 46 as hereinafter described. The purpose of this spring is such that when the ram piston 83 is projected from the ram cylinder against the roller 110 it will compress the spring 146 against its seat 46 during the load lifting operation. Upon release of the ram piston the spring will force the outer end of the ram piston back into the cylinder and permit the load-carrying member to lower.

By loosening the four screws 80 the entire unit shown at the lower portion of Figure 2 may be removed from its seats 50 and 52 formed in the hollow inner walls of the chassis. This unit comprises the head 82 and the connected ram cylinder 84 carrying the ram 86. The plate 75 of the unit forms a shoulder 150, see Figure 7, against which a sleeve 152 is clamped. The opposite end 70 of this sleeve clamps against a shoulder 154

formed on a head or casting 156. In addition, this casting 156 is provided with a threaded surface 158 and a relatively small chamber 160 extending beyond the surface 158, which chamber 160 connects by means of a passageway 162 with a reservoir 164 which is formed by a second sleeve 166 which threads into the threaded bore 158 of the end section 156 and into similar threads 168 of an extension 170 on the head plate 75. Thus the two sleeves 152 and 166 are maintained in spaced apart relation to form the oil or liquid receiving reservoir. The end section or casting 156 is provided with a hollow bore 172 which registers with a central conical cavity 174 formed in the end of the plate 75 and centrally of the 15 annular well 170. The ram 176 is disposed in this elongated bore centrally of the longitudinal axis of the two sleeves 152 and 166. The ram 176 is of smaller diameter than the sleeve 166 so as to leave the annular space 178 therebetween. This space communicates with the small chamber 160. One end of the ram 176 is provided with the usual flexible gasket 180 held in place by the nut 182. This ram 176 is provided with an elongated central bore 184 into the outer end of which is threaded as at 186 the circular head 119 that contacts the roller 110 of the load-lifting member, see Figure 4. The threaded bore 186 of this ram 176 is provided with a threaded screw 192 which has an end slot for turning it, and confined and adjusted by this plug 192 is a coil spring 194 which presses against a plunger 196 of a diameter smaller than the bore 184 in the ram and at the other end of this plunger 196 presses against a ball valve 198 which controls a passage 200 formed in the threaded extension 202 of the ram 176. It is this extension 202 that receives the nut 182 holding the flexible washer and packing in place. The ram 176 is provided with a transverse passageway 204 which connects with the 40 space 206 formed between the plunger 196 and the inner wall of the bore 184 of the ram, and this transverse passage 204 in turn connects with the space 178 between the inner sleeve 166 and the ram, which passage in turn connects by means of the chamber 160 and the passageway 162 with the reservoir.

The spring 184 may be adjusted by means of the threaded plug 192 to any desired tension to control the pressure at which the ball valve 198 is held against its seat, and this in turn controls the pressure in the ram cylinder well or chamber 174, as hereinafter explained.

The outer angular surface of the casting 156 seats in the circular bore of the web 50, as shown in Figure 7. In addition the sleeve 84 when assembled to the section 156, and the plate 75 fit within the circular bore formed in the web 52. The plate 75 is bolted by means of the bolts 80, as hereinbefore described, to the main chassis 2. The head 82 is hollow and is provided with internal walls 208 which are provided with a bore 210 the central axis of which lies at an angle of about thirty degrees with the central longitudinal axis of the ram cylinder and ram, and is also provided with a bore 212 the internal walls of which are threaded to receive the threaded end of a relief valve actuator 214. The longitudinal axis of the bore 212 is likewise disposed at thirty degrees and is parallel to the central axis of the ram cylinder and is, in fact, almost parallel with the longitudinal axis of the bore 210 for the high pressure pump cylinder piston. In the bore 210 is a high pressure pump cylinder 216 herein shown as an elongated sleeve, the outer ends of which are 75

provided with the spaced threaded portions 218 and 220, and making a tight fit with the inner end of this sleeve 216 is a ball valve cage 222 which is smaller in diameter than the inner wall 5 of the bore 210, and formed integral with or making a snug, tight fit with the ball valve cage 222 is a conical head 224 formed with a liquid passageway 226. The ball valve cage is provided with suitable passages 228, 230 and 232, and the ball valves 234 and 23 which control the ingress and egress of the liquid to the high pressure pump cylinder 216. A high pressure pump piston 236 is reciprocable in this cylinder. The cylinder is held in its bore in the unit 82 by means 10 of the annular screw 238 and the packing 240, and the outer end of the sleeve 218 is sealed by the threaded cap 242 which is apertured to receive the piston 236 therethrough. The piston 236 is provided with the usual flexible washer and 15 the outer end of the piston is provided with a yoke 246 which is connected to the piston by means of the threaded connection 248, the furcations of the yoke 246 engaging pin 250 carried by the sector-shaped plates 252 and 254 herein- 20 after described.

The central liquid passage 226 of the high pressure pump cylinder connects with another passage 258 formed in the unit or casting 208, which in turn connects with the transversely disposed 25 passage 260 which branches and connects as at 260 with the central chamber 174 of the ram cylinder and with another passage 262, the exit of which is controlled by a ball valve 264. The seat of this ball valve on its seat is in turn controlled 30 by a projection 266 on the end of the elongated valve rod 214. An elongated passage 268 empties into the reservoir at one end and connects with the passage 262 controlled by the ball valve 264. In turn there is another passage 276, shown in dotted lines, which connects the reservoir with a space 278 formed between the conical nose 224 of the high pressure pump cylinder and the conical walls of the bottom of the bore 210. The pressure relief operating rod 214 passes through a threaded annular cap 280 that seals packing 282 against its confronting walls to prevent the escape of the liquid at this point. The outer end of the valve actuator rod 214 has pinned thereto as at 284 a cap 286 which is provided with one part 288 of a universal joint which pivotally connects to another portion 290 of a universal joint in turn connected to a connecting rod 292 which has furcations 294 engaging a pin 296 therebetween. This pin is formed on the inner side of a sleeve 298 having a flange 300 forming an annular keyway 302. This sleeve 298 makes a tight fit in an elongated hollow handle 304 which turnably lies within a socket 306 of an oscillatable head 308. This socket carries two elongated ears or bearing members 310 which pivot about the two spaced pins 312, see Figure 6, which pins have pivotal bearings in registering openings 315 formed in a pair of tongues 314 carried by and formed on the unit 82, which is that part of the 40 unit or head immediately surrounding the relief valve rod 214. By reference to Figure 6 it will be seen that the pins 312 are rotated on their outer ends into the legs 310 of the actuator handle socket 306 and then inwardly of the threaded part are provided with a further bearing part which passes through the apertures of the two furcated supports 314 and inwardly of this bearing part the pins 312 are provided with a reduced 45 diameter which passes through the apertures 316

of the sector 252 whereby they may be oscillated. Intermediate of the two sectors is a space through which the interconnected joints of the universal lie. In this manner a construction is provided whereby the universal is interconnected for universal movement about the central axis of the pins 312 about which the actuator handle 338 oscillates so that the relief valve actuating stem 214 may be mounted centrally of the head 82 whereby only a single universal need be provided between the relief valve and the oscillatable handle that operates the high pressure pump piston while at the same time permitting the relief valve to be turned in any position of the actuating handle. The sector 252 is provided with registering apertures 316 which in turn pivot likewise on the pins 312. These two sectors are provided with the rigidifying pin 318 which interconnects them. These sectors are provided with the two parallel stops 320 and are likewise provided with the registering notches 322 and the spaced registering notches 324. The stops are adapted to contact a wall portion 326 of the head 82 to prevent further movement in that direction and the notches 322 and 324 are adapted to be engaged by the latching shoe 328 which has a threaded hole 330 into which a pin 332 is threaded and carrying a head 334. This pin 332 passes through a bore 336 in the handle socket member 306. A coil spring 340 normally projects the latch 328 into engagement with whichever one of the notches 322 and 324 it is desired to be engaged with.

Means is provided for holding the sleeve 298 and the handle 304 in position within the socket 306 and this comprises a pin 342 having the head 344 and a spring 346 which normally maintains the head within the socket 302 while permitting the sleeve 298 to be turned by turning the handle 304. However, when desired, by pulling outwardly on the head 344 the pin 343 is moved outwardly whereupon the handle 304 and the tight fitting sleeve 298 may be withdrawn from the handle socket, the pin 296 of the handle 298 freely coming out from between the furcations in the furcated end of the rod 292. When thus removed the rod 292 is inaccessible for turning. However when the handle and its sleeve with the cross pin 296 are reinserted in the handle so that the cross pin 296 engages between the furcations of the rod 292, then by turning the handle 304 the rod 292 may likewise be turned, which through the universal connection turns the valve operating release rod 214 to unscrew it from its seat and thereby permit the ball 264 to be removed from its seat by the pressure in the ram cylinder whereupon liquid will flow from the ram cylinder well through the passage 260, thence through the passage 262, past the ball 264, through the passage 268, into the reservoir and the load member will thereupon lower. On the other hand, when the valve rod 214 forces the ball to its seat and through the oscillation of the handle member and the sector 252 the high pressure pump piston 236 is operated, liquid will be drawn from the reservoir through the passage 276, into the space 278, see Figure 11, between the conical nose on the pump cylinder and the inner bore, thence through passage 348, past the ball 234, to cause the liquid to enter the pump cylinder. Then upon downward movement of the pump piston 233 the ball 234 will be forced against its seat, to close the passage 348, and the liquid will pass through the passage 228 to release the ball valve 236 from its seat, which will allow the liquid to pass through the cross

passage 232, thence down the central passage 226 into the passage 256, through the cross passage 258, into the ram cylinder, to move the ram outwardly of the ram cylinder.

When the ram cylinder is thus moved outwardly, and if the pressure should get too high, that is, greater than the tension of the spring 194, then the plunger 196 is moved to the left to allow the ball valve 198 to move from its seat so that liquid will then be forced through the passage 206 past the ball valve 198, and through the passage 204, thence into the passage between the ram and ram cylinder which connects to the annular passage 160 having at its lower end the passageway 162, back through which the liquid will pass into the reservoir.

In certain instances it is desirable to raise the work holder 122 quickly up to the load, and thereafter to raise the load relatively more slowly. In order to accomplish this there is provided the double acting high pressure cylinder and piston and valve construction shown in Figures 10 to 13, which replaces the cylinder and piston construction shown in Figure 7, all of the other parts of Figure 7 remaining the same. In explaining this construction, by reference to Figure 10, the casting 208 is provided with the same bore 210 which at its inner end is formed with inwardly extending conical walls 211, which communicate by means of the passage 256 with the cross passage 258 shown in Figure 7. In addition, the conical walls have another passageway 276 therein which is shown in dotted lines in Figure 7 as communicating with the reservoir for the ram cylinder. The conical walls 211 at their juncture with the passageway 256 make a tight fit, as shown at 257, so that liquid cannot pass from the space 278 to the conduit 256 except that it pass by way of the ball valve cage 350. As shown in Figure 10, this ball valve cage 350 of this construction differs from the ball valve cage shown in Figure 7. The head casting 208 is threaded at its outer end as shown at 352 and into this threads an inwardly finished steel tubing 354. The outer end of this steel tubing is provided with an annular outwardly flared portion 356 to receive a ring-like packing retainer 353 to hold in place the packing 360. This packing tightly engages a piston 362, one end of which is provided with the furcated portion 364 to engage the pin 250 of the oscillatable sector 252 shown in Figures 7 and 8. This piston 362 is provided with a centrally disposed hollow bore 366 which extends longitudinally axially of the piston. Within this bore 366 is located a high pressure piston 368. The piston 362 acts at a lower pressure than does the piston 368. The higher pressure piston 368 is provided centrally axially and longitudinally of the piston with an elongated bore 370 which terminates at its upper end in a narrower bore 372 which communicates with the high pressure cylinder chamber 374 formed in the larger piston 362. A flexible packing 376 is mounted on the upper end of the piston 366 and is held in place by a retaining collar 378 held in position by a nut 380 which threadedly engages a reduced portion 382 formed on the upper end of the high pressure piston. The elongated high pressure piston 368 has on its opposite end a threaded portion 384 which threads into a threaded bore 386 of the valve cage 350. The liquid passageway 370 in the piston 368 extends clear through the projection 388 of the piston 368 which projection is threaded into the bore 386 and the end of this bore 370 discharges

into a chamber 393 which by means of a passage 392 opens onto the lower end of the valve cage or block 350 at the point 394. The terminal opening of this central passageway 392 is formed as an enlarged chamber 393 controlled by the ball valve 393. In addition to the foregoing, the ball valve cage 350 has a terminal passage 400 controlled by the ball valve 402 which closes on a seat 404 controlling a passage 406 which has a right angled passage 408 terminating at an annular countersunk or cut-out passage 410 on the recessed side wall of this valve cage. The valve cage 350 is press fitted as for instance at 351 annularly to the inner wall of the metal tube 354 which in turn is threaded to the stationary casting 208. Therefore the cage or block 350 is stationary as is also the piston 368 which is threaded as at 384 to the cage or block. In addition there is a conical metal end piece 412 which is press fitted as at 414 to an inner countersunk portion 416 of this valve cage 350, and the outer conical end 257 of this piece 412 makes a permanent fit or tight seat on the wall or seat 211 of the bore 210. As stated, before, the outer annular wall of the valve cage 350 is spaced from the inner wall of the bore 210 to provide a liquid passageway which connects with the space 278 and also with the countersunk portion 410. The valve cage 350 is provided intermediate its top and bottom with a pair of cross bores at right angles to each other.

These intersecting cross bores are 418 and 420, see Figure 13, and they are preferably at right angles to the longitudinal axis of the central bore 392 and also to the longitudinal axis of the bore 444. The bore 420 has a reduced portion 422 which terminates as at 424 in the annular recess 410. The opposite end of this bore 420 is closed by a threaded plug 426. This plug 426 has an extension 428 around which a coil spring 430 is retained, the outer end of which spring bears against a ball valve 432 which seats upon the valve seat 434, see Figure 13, controlling the bore or conduit 422. The other conduit 418 which is arranged at right angles thereto and intersects the bore 420, has one end closed by a threaded plug 436 and provides a valve seat 438 normally closed by a ball 440. The valve seat connects with a smaller port 442, see Figure 12, which opens into an elongated vertical bore 444 extending from the top face 446 of the valve cage which is in communication with the space made by the lower end of the outer pressure piston 362 when the latter is moved upward in its cylinder. The lower portion of this vertical passage 444 terminates in a valve seat 448 controlled by the ball valve 450. There is a spring 452 confined between the top of the conical end 412 and the valve seat 448 for holding the ball 452 to its seat normally. The bore in which the ball valve 450 seats is connected by means of a short lateral passage 454, see Figure 12, with the annular recessed space 410 surrounding the side walls of the ball valve cage.

In the operation of this device, when the larger piston 362 is drawn upwardly, the ball valve 402 will be raised from its seat so that liquid is drawn from the reservoir 152 through the passageway 276 to the chamber 278, see Figure 10, thence by way of the recessed portion 410 to the passageway 408, to the passageway 406, past the raised ball 402, into the larger cylinder, caused by the raising of the larger piston 362. So also on the rise of the piston 362, liquid will be drawn from the reservoir through passage 276, space 75

278, the annular recess 410, through the passage 422, past the ball 432, thence through central passage 392, through the piston passageway 370, 372, to the high pressure cylinder chamber 374 above the top of the smaller piston 368. Upon the down stroke of the piston 362 the ball valve 402 closes and the ball valve 432 closes. Liquid will thereupon be forced by the lower end of the piston down through the passage 444, see Figures 11 and 12, through the passage 442 past the ball 440 which is pushed from its seat, and thence down the central passage 392, past ball 398 which is pushed from its seat, thence through a passage 413 which is disposed centrally of the conical end piece 412, thence through passage 256, thence through passage 258, see Figure 7, into the main ram cylinder 174 which will tend to urge the ram to the left, see Figure 7. Simultaneously, the liquid that was confined in the high pressure cylinder space 374, see Figure 10, is likewise forced through the passage 372, through longitudinal passage 370, straight through the central passage 392, past the ball valve 398, through passages 413 and 256, to passage 258, into the ram cylinder chamber 174, so that there is produced a pressure in the ram cylinder equal to the combined volume of the liquid that is forced both by the piston 362 and also by the piston 368. This will raise the lifting head 122 much more quickly than the single piston 238 of Figure 7. This action will take the lifting head 122 up to the load. At this time the back pressure due to the load will increase and cause the fluid in the larger outer pump 362 to by-pass through the ball valve 450 which will open against the tension of the spring 452 which has a predetermined built-in pressure, and release the fluid from pump 362 through the passageway 454 and into the annular space 410 and thence into passageway 278 back into the reservoir. Simultaneously with this release of the liquid from the larger piston back into the reservoir, but due to the movement of this larger outer piston, the smaller high pressure piston 368 is forcing the fluid in the cylinder chamber 374 to pass through the passages 372 and 370, chamber 390 and passage 392, the valves 440 and 432 maintained closed upon the seats 438 and 434, and forcing the liquid directly through the passage 392, past the ball 398, into the passage 413, 256, 258, into the ram cylinder chamber 174 to continue the slower movement of this ram to the left, whereby now more slowly to raise the load-carrying member 122. Thus by reciprocation of the pump piston, the load-carrying member 122 will be first quickly raised to the load whereupon the additional back pressure of the load will relieve the liquid that comes from the larger piston and cause it automatically to flow back into the reservoir, whereas the liquid which is under the influence of the smaller piston 368 continues to be forced through the passages as hereinbefore mentioned, into the ram cylinder, to cause the slower movement of the ram to lift the load. Thus the effect of the larger piston is automatically cut out during reciprocation of the piston operating mechanism and the smaller higher pressure pump piston is continued. In short, in the first part of the operation both pistons operate simultaneously to produce a quick approach of the load-lifting member to the load, utilizing speed instead of force, whereas in the second part of the operation the larger piston is automatically cut out and the smaller piston remains operative to lift the load. Furthermore,

when the load becomes too excessive for the pump, the pressure built up in the ram cylinder chamber 174 will open the valve 193 against the adjusted tension of the spring 194 to pass the liquid through the passages 204, 178 and 162 into the reservoir.

From the foregoing it will be appreciated that the entire valve mechanism is housed and retained in the valve cage which is located between the pump cylinder and the bottom of the pump cylinder bore, thereby eliminating the necessity of extra valves and valve seats in the base. The entire valve mechanism may be easily removed by unthreading the pump cylinder from its bore.

The spring 430 which closes the ball valve 432 also acts as means to retain the ball 438 against its seat 439 while at the same time permitting it to become unseated.

Obviously the invention is not limited to the specific details of construction disclosed herein but is capable of other modifications and changes which do not depart from the spirit and scope of the appended claims.

Having thus described my invention, what I claim as new and desire to secure by Letters Patent is:

1. A floor jack of the type comprising an elongated, relatively low chassis adapted to be disposed horizontally on the ground, one end of said chassis providing a hollow housing having a circular opening at one end, in combination therewith an hydraulic unit comprising a head having means for connection to the end of the chassis adjacent the opening thereof, said head including a portion provided with a pair of bores, one substantially centrally of the head for a release valve and the other for a high pressure pump cylinder, a piston reciprocable in said cylinder, a valve cage disposed in said pump cylinder and including oil passages therein, said head portion including additional passages communicating with the high pressure pump cylinder and the release valve, a pair of spaced sleeves mounted on said head portion providing a ram cylinder and a liquid reservoir communicating with said passages in said portion, said head portion providing a ram cylinder chamber communicating with said ram cylinder a ram mounted in said ram cylinder and spaced in part from the walls of said ram cylinder. a second head interconnecting the two spaced sleeves, said second head being provided with a central perforation through which the ram is adapted to reciprocate and through which said ram fits in a snug manner, packing means associated with said second head, said packing means contacting the outer annular walls of said ram, means providing a chamber in said second head communicating with the space between the inner wall of said ram cylinder and said ram, means providing a passage connecting said chamber with the reservoir, said ram having a hollow bore, the walls of said bore of the ram providing a valve seat and a central passage connecting said valve seat with the ram cylinder chamber centrally of said ram, an elongated plunger mounted in the bore of the ram, there being a space between said plunger and the inner wall of the bore of the ram, said ram having a lateral passage disposed adjacent that end of the ram which has the valve seat, a valve normally disposed on said seat, said valve being normally contacted by said ram plunger, a coil spring in the opposite end of the bore of the ram and contacting the outer end of said

plunger, and an adjustable threaded plug mounted in said bore to adjust the tension of said spring, and a head threadedly mounted on said ram.

- 5 2. An hydraulic jack comprising a base having apertures therein and a ram cylinder chamber, a pair of sleeves mounted on said base in spaced relation to provide a reservoir, the inner sleeve providing a ram cylinder, a ram reciprocably mounted in said inner sleeve and spaced throughout a portion of its length from the walls thereof to provide a liquid passage, a head spaced from the base and interconnecting said sleeves at their outer end, said head being bored, a ram 10 snugly reciprocable through the bore of said head, packing means in said head adapted to engage the annular walls of said ram, said ram having a central bore therethrough, the inner end of said bore providing a valve seat and a centrally disposed passage connecting with the ram cylinder chamber, said ram having a lateral passage connecting the bore of the ram with the space between the outer wall of the ram and the ram cylinder, said head having a passage formed therein connecting with the space between the inner wall of the ram cylinder and the outer wall of the ram, means formed in said head connecting said passage with the reservoir, an elongated plunger mounted in the bore of said ram, a ball valve disposed between the plunger and said valve seat, the outer portion of the inner bore of said ram being threaded, an adjustable plug engaging the threads of said bore, a coil spring disposed between said plug and the outer end of said plunger for resiliently engaging the ball on its valve seat, a high pressure pump mounted in a bore in said base, a release valve mounted in another bore of said base, said base including valve controlled passages interconnecting the ram cylinder chamber and the reservoir and the high pressure pump, and means for reciprocating the piston of said high pressure pump and for operating said release valve.
- 15 3. A cylindrical block-like hydraulic pumping mechanism of a jack comprising an elongated cylindrical block having opposed faces, the annular cylindrical wall between said faces being provided with an annular countersunk portion to provide a liquid passage, said block along its central axis parallel with said countersunk portion being provided with a central passage extending from face to face of said block, the end of said passage at one of said faces of said block being provided with a valve seat, said block at the opposite face being provided with an opening disposed laterally of said central passage and provided with a valve seat and a connected passage extending part way through said block in a direction substantially parallel with the central passage thereof, said connected passage having a lateral extension connecting with the annular countersunk portion of the block, said block having a third passage spaced from the central passage and extending substantially parallel to the central passage of the block, said third mentioned 20 passage extending from said second face of the block to a point adjacent the opposite face, at which point said third mentioned passage is provided with a valve seat and a lateral passage connecting with the annular countersunk portion of the block, said block also having a pair of passages transversely disposed with respect to each other and extending completely through the block in a direction at right angles to the central passage through the block, said angularly dis-
- 25 30 35 40 45 50 55 60 65 70 75

posed passages interconnecting with the central passage, one of said pair of angularly disposed passages being provided with a valve seat and interconnecting with said third mentioned passage, said passage at its other end having a plug to obstruct connection with the annular countersunk portion, the other mentioned passage of said pair of passages having a connection with said countersunk portion and having an associated valve seat and valve, and the opposite end of said last mentioned passage being blocked from communication with said annular countersunk portion.

4. In a floor jack of the type having a chassis adapted for disposition horizontally on the ground and which chassis has a load lifting member shiftably mounted thereon for elevation to raise a load and which also has an hydraulic unit mounted thereon, said unit including an actuatable ram positioned when the unit is so mounted to actuate the load lifting member, and wherein in said unit further includes hydraulic pumping means having a piston and a release valve disposed substantially centrally of the unit, there being means for mounting said unit on said chassis, and said unit carrying thereon a pair of spaced, elongated supports having bearings on their outer ends, in combination therewith a turnable handle socket for actuating said pump piston and for actuating said release valve, said handle socket having furcations provided with registering apertures, a pair of spaced pins passing through the apertures of said furcations and engaging the apertures in said spaced bearings, an oscillatable sector having spaced openings, said pins having bearing members on their inner ends adapted to enter the bearing members of said spaced sector, said spaced sector being rigidly interconnected but being disposed between said elongated bearing members of said head, spaced notches on said sector and a shiftable latch mechanism carried by said handle socket and adapted yieldingly to engage in a desired notch of said sector to interconnect the handle socket and sector for oscillation together, an elongated tubular handle, a sleeve carried by an end of the tubular handle, said end being insert-

able in said handle socket, said sleeve having a connector therein, an elongated turnable actuator mounted in said handle socket and projecting into the socket aperture detachably to be engaged by the connection of said socket sleeve whereby said connector may be turned by turning said handle, and a universal connection on the other end of said elongated connector and connected to said relief valve, said universal being disposed between said elongated bearing members of said base, and shiftable latching means carried by said handle socket for allowing said handle to be withdrawn from said handle socket, or alternatively for locking said handle to said handle socket while at the same time permitting said handle to turn relatively to its socket to turn the valve.

JOSEPH J. MUELLER.
